UNITED STATES PATENT OFFICE.

JOHN SCHUMACHER, OF LOS ANGELES, CALIFORNIA.

JOINT TRIMMER FOR PLASTER BOARD AND THE LIKE.

Application filed November 5, 1925, Serial No. 67,097. Renewed November 23, 1927.

This invention relates to a tool for dressing the adjoining margins of plaster board panels and the like preparatory to covering the same so as to conceal the joints. It has 5 been found that an effective means of covering joints of this character comprises a chamfered face tape laid in a corresponding depression at the joints of plaster board. This serves admirably to produce a flush 10 finished surface.

The joints often become filled with foreign matter and it is advantageous to clean the same, and also to enlarge the joint crack to a uniform size, so that a cement or plaster 15 putty may be inserted therein to fill and bind the panels. This invention relates to a device for treating the adjoining face margins of plaster board panels to produce a chamfer and also to clean the joint crack. Thus, 20 the joint will be ready for the reception of plaster putty, if so desired, and of tape to cover the joints.

The primary object of this invention is to provide a tool adapted to be used to dress 25 the marginal faces and clean the joint at one operation. Another object of this invention is to provide a tool having faces adapted to be covered by a sheet of abrasive material in such a manner that it may be readily 30 replaced. A further object of this invention is to provide a structure of the character described with a removable blade for cleaning the joint crack, and also for guiding the tool. In addition to the broader objects of 35 this invention, there are certain details of structure whereby a simple, compact, economical, and easily manipulated tool is obtained.

These objects together with other objects 40 and corresponding accomplishments are obtained by means of the embodiments of my invention illustrated in the accompanying drawings, in which:

Fig. 1 is a side elevation of one form of 45 tool embodying my invention, a portion thereof being broken away and shown in longitudinal section; Fig. 2 is an end view of the tool as seen looking in the direction of the arrows 2 of Fig. 1; Fig. 3 is a section 50 as seen on the line 3-3 of Fig. 1; Fig. 4 is a transverse section similar to Fig. 3 showing a section through another form of my tool having no cleaning blade; Fig. 5 is a perspective view showing the fragment of 55 adjoining plaster board panels after having been dressed by my improved tool; Fig. 6

is a side elevation of another form of tool embodying my invention, a fragment thereof being shown in vertical section; Fig. 7 is a section as seen on the line 7-7 of Fig. 6; and Fig. 8 is a fragmentary sectional view through adjoining panels showing a chamfered tape in position covering the joints.

Referring more particularly to Figs. 1 to 4 inclusive, a tool is shown, which may be conveniently made of stamped metal. This tool comprises a body having a back 10 to which the abrasive is adapted to be secured. The back has side walls 11 and inwardly bent underhanging margins 12. A hollow back is thereby provided. Extending upwardly from the back is a handle portion 13 ending in a rounded hand grip 14. The structure just described may be bent from a single sheet of metal, the handle having a slot to receive a locking plate 15. This plate is secured to the handle by any suitable means such as rivets 16. It will be noted that the handle ends short of the body and that the locking plate 15 extends beyond the back. The plate is provided with enlargements 16 at the ends, which are bored and threaded to receive screws 17. A face plate is mounted within the back. This plate has sloping sides 18 and at the center is provided with a longitudinally extending rib 19 having a slot. The marginal edges of the face plate are offset to provide ledges for engaging the walls 12 of the back. The back is extended to form seats 20 which may be disposed beneath the screws 17. The screws when forced downwardly will hold the face plate in position against the underhanging walls 12 of the back. Covering the face of the face plate and frictionally clamped in position by the ledges and the walls 12 is a strip of abrasive material 21. This sheet of material may be sand paper or the like. It is forced into the recess in rib 19 and held in position by a blade 22 which has teeth on the lower edge thereof. Blade 22 is held in the rib by means of pins 23 which extend transversely through the blade and the walls of the rib.

It is obvious that the sheet of abrasive material may be changed easily. To do this screws 17 are backed up to release the face plate from the back, permitting the latter to be removed. Pins 23 are then removed releasing blade 22. A new sheet of abrasive 105 may then be installed, and a new blade if desired.

In Fig. 4, a back is shown having a handle which is the same as that already described. The construction differs from that in having a face plate 24 which is not provided with a blade, the result is that there is a chamfered surface as before, but no blade extending from the apex thereof.

Referring to Figs. 6 and 7, a metal frame is shown having a lower face provided with 10 an opening through which the abrasive and blade may extend. There is in effect, a casing having the lower face thereof composed of underhanging border bars 25 and 26, all integral. This case has end walls 27 15 and inwardly turned top walls 28 provided with brackets 29, between which is mounted a handle 30. The handle may be wood and is conveniently secured in position by means of the screws 31. Bosses 32 are provided in 20 the top wall 28 and are threaded to receive lock screws 33. The face member may be made of wood and comprises a block 34 adapted to fit within the casing and having a protruding portion of such dimensions 25 that it snugly fits the opening in the lower face of the casing. This protruding portion is provided with sloping faces 35 intersecting at a slot 36. Arranged to be mounted in the slot is a cleaning blade 37 which is 30 adapted to extend through the opening in the lower face of the casing and to have extensions 38 overhanging the border bars 25. The chamfered face of the block is covered by an abrasive sheet as indicated by 39, 35 which is folded to extend into the slot 36. The blade 37 is placed in position, and the block mounted within the casing, the screws 33 then being tightened to hold the block in position.

40 The tool is used in the following manner: After the adjoining panels have been placed in position, the blade is inserted in the joint A between panels B and C of plaster board. The tool is then moved backwardly and forwardly so as to chamfer down the exposed faces of the plaster board as indicated by b and c. The joint is cleaned by means of the blade which also acts as a guide to maintain the tool in position while being used. The 45 tool as shown in Fig. 4, may be used, this tool will not clean the joints but will only chamfer the margins of the adjoining pieces of plaster board. Plaster putty may be inserted in the joints to fill the latter and act 50 as a binder. The joint may then be covered by means of a tape D which may be made of paper and has one face thereof chamfered to

correspond with the chamfer produced on the adjoining panel. When the tape is placed in position, its exposed face will be 60 flush with the faces of the plaster board thereby producing a smooth wall.

What I claim is:

1. A tool of the character described comprising a back, a face member removably mounted thereon, said face member having sides sloping toward an intermediate portion thereof, an abrasive sheet secured over said face member, and a ridge cleaning blade projecting from said face member. 65

2. A tool of the character described comprising a back having underhanging edge members, a face member arranged to be removably supported on said edge members and having an inwardly extending slot intermediate the edge portions, an abrasive sheet clamped between said edge members and said face member over the latter, and a ridge cleaning blade disposed in said slot and projecting from said face member. 70

3. A tool of the character described comprising a back having underhanging edge members, a face member arranged to be removably supported on said edge members and overlapping the latter, said face member having an inwardly extending slot extending the length thereof at the center, an abrasive sheet clamped between said edge members and said face member over the latter, a cleaning blade disposed in said slot 85 and projecting from said face, the ends of said blade overlapping the edge members and means on said back for forcing said face member against the edge members so as to lock the latter in position thereon. 90

4. A tool of the character described comprising a back having underhanging edge members, a face member arranged to be removably supported on said edge members, said face member having sides sloping toward an intermediate portion thereof provided with a slot, an abrasive sheet clamped between said edge members and said face member over the latter, a cleaning blade disposed in said slot and projecting from said 100 face member, said cleaning blade having its ends overlapping the edge members, and means on said back forcing said face member against said edge members so as to lock the latter in position thereon. 105

In witness that I claim the foregoing I have hereunto subscribed my name this 28th day of October, 1925.

JOHN SCHUMACHER.
